CONTAINER WITH HINGED COVER

Neil S. Waterman, Scarborough, N. Y.

Application March 18, 1950, Serial No. 150,434

2 Claims. (Cl. 220—31)

1

This invention relates to new and useful improvements in containers with covers.

More particularly, the invention proposes a new hinge construction for a container and its cover by which the cover is hingedly connected with the container. One hinge may be used for each container and cover, or more than one hinge, as for example, two hinges may be arranged on opposite sides of the container and cover, and may operate so that the cover may be hinged open by selectively using either of said two hinges.

The new hinge construction is characterized by trunnion hinge sections frictionally releasably engaging in socket hinge sections in order that the hinge sections may hinge in the usual way, and may be separated whenever desired. Moreover, the construction is exceptionally simple and lends itself for use with rigid type plastic material containers.

An important object of this invention also resides in the construction of a container formed from a body and cover and provided with two of the new hinges on opposite sides so that the cover may be hinged open using either one of the hinges as a hinge. The other hinge then acts as a latch when the cover is closed.

Another characteristic feature of the invention resides in providing a cover with one or more projecting lugs provided with a trunnion hinge section on each end of each lug and cooperative with an open top body having vertical walls provided with cutouts into which the lugs engage, and the side portions of said cutouts being provided with top and end walls which are provided with socket hinge section recesses for receiving said trunnion hinge sections in order to form hinges for said cover.

It is an object of this invention to form the trunnion hinge sections with beveled ends and to form the socket hinge section recesses with inclined ends in the top walls of said side portions into and through which the beveled ends of the trunnion hinge sections may pass when said lugs are engaged into said cutouts in order that the trunnion hinge sections may seek positions slightly beneath said top walls when in said socket hinge section recesses, so that the beveled tips of the trunnion hinge sections will engage beneath the bottom faces of said top walls when said cover is hinged coaxially of said trunnion hinge sections to open positions on said body in order to hold said cover pivotally on the body.

The new construction is exceptionally simple and provides an efficient hinge or hinges by which the cover is hingedly mounted on the body.

2

Another object of the invention is the construction of a device as described which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a plan view of a container with a cover constructed in accordance with this invention.

Fig. 2 is a front elevational view of Fig. 1.

Fig. 3 is an end view of Fig. 1.

Fig. 4 is a fragmentary enlarged sectional view taken on the line 4—4 of Fig. 1.

Fig. 5 is a fragmentary enlarged sectional view taken on the line 5—5 of Fig. 1.

Fig. 6 is a fragmentary enlarged sectional view taken on the line 6—6 of Fig. 1.

Fig. 6a is a fragmentary enlarged detailed view of the back left hand corner of Fig. 1, but illustrated with the cover of the container pivoted upwards to a vertical position.

Fig. 7 is a plan view of another container with cover constructed in accordance with another form of this invention.

Fig. 8 is a front view of Fig. 7.

Fig. 9 is a fragmentary enlarged sectional view taken on the line 9—9 of Fig. 7.

Fig. 10 is a fragmentary enlarged sectional view taken on the line 10—10 of Fig. 7.

Fig. 11 is a fragmentary enlarged detailed view of one of the corners of the container, illustrated per se.

Fig. 12 is a fragmentary enlarged detailed view of one of the corners of the cover, illustrated per se.

Fig. 13 is a fragmentary plan view of the container portion and cover portion shown in Figs. 11 and 12 assembled and illustrated with the cover pivoted vertically upwards to an open position.

The container with hinged cover, as illustrated in Figs. 1 to 6 inclusive, includes a cover 10 of rigid type plastic material having a projecting side or lug 11 provided with a trunnion hinge section 12 on each end and said trunnion hinge sections having beveled ends 13. This cover is associated with an open top body 14 of rigid type plastic material having a vertical wall 15 provided with a cutout 16 into which said projecting side or lug 11 engages. The body 14 also has end

walls 18 and top flanges or top walls 17 projecting from said end walls 18. To the sides of said cutout 16 the top walls 17 and end walls 18 are provided with socket hinge section recesses 19 for receiving said trunnion hinge sections 12.

The socket hinge section recesses 19 have inclined ends 20 extending through said top walls 17 through which the beveled ends 13 of said trunnion hinge sections 12 pass when said lug 11 is engaged into said cutout 16. The trunnion hinge sections 12 are a tight fit in said socket recesses 19 so that it requires a little force to engage and remove the trunnion hinge sections from the recesses. Normally, the trunnion hinge sections 12 are located slightly beneath the top walls 17, see Figs. 3 and 5, when said trunnion hinge sections are positioned in said socket recesses 19. With this construction the beveled tips of the trunnion hinge sections 12 will engage the bottom faces of the top walls 17 when the cover 10 is pivoted to an open position upon the body 14 in order to hold said cover 10 pivotally on said body 14.

In the particular design and construction of the container illustrated, the trunnion hinge sections 12 comprise the ends of a rod 20' which extends across the bottom face of the cover 10 and which is cemented in position to the cover 10. The ends of the rod 20' project from the ends of the lug 11 and form the said trunnion hinge sections 12. The side and front walls of the container 14 have beveled top edges 21 which are engaged by complementary bevels along the edges of the cover 10. The cover 10 is also provided with a front projecting handle portion 22 projecting outwards of the front wall of the container 14 by which the cover may be easily gripped and pivoted to open and closed positions.

The operation of the new container and cover may be understood from the following:

In Fig. 1 the cover 10 is shown in its closed position on the container 14. In this position it may be removed from the container by firmly gripping the cover and container and pulling them apart. The trunnion hinge sections 12 merely snap out from the open socket recesses 19 during the disengagement of the cover from the container. The cover 14 may be re-engaged upon the container by placing it across the top of the container and forcing the trunnion hinge sections 12 down into the socket recesses 19.

When the cover 10 is hinged open on the container 14 the tips of the trunnion hinge sections 12 engage beneath the bottom faces of the walls 17 and pivotally hold the cover 10 connected with the container 14. Thus the cover may be pivoted open and closed without these parts coming apart during the pivoting operation.

In Figs. 7 to 13 inclusive, another embodiment of the same invention has been disclosed. More specifically, a cover 25 of rigid type plastic material is provided with a pair of projecting sides or lugs 26 formed on its front and back edge portions. These lugs 26 are provided with trunnion hinge sections 27 on their end portions. The trunnion hinge sections 27 have beveled ends 28. The cover 25 is cooperative with an open top body 29 of rigid type plastic material having vertical walls 30 along its front and back sides. These vertical walls 30 are provided with cutouts 31 into which the said lugs 26 engage. The side portions of said cutouts 31 have top walls 32 and end walls 33 which are provided with open socket hinge section recesses 34 for receiving the trunnion hinge sections 27 so as to form two separate hinges for said cover 25. The

top walls 32 and the end walls 33 are formed by cavities 33a formed in the vertical walls 30 and extending upwards from the bottom faces of said vertical walls 30.

The socket recesses 34 have inclined ends in said top walls 32 through which the beveled ends 28 of said trunnion hinge sections 27 pass when said lugs 26 are engaged in said cutouts 31. The trunnion hinge sections 27 are tight fits in said socket recesses 34 so that it requires a little force to engage and remove said trunnion hinge sections from said socket recesses. Said trunnion hinge sections 27 are normally located slightly beneath the top walls 32 (see Fig. 9) so that the beveled tips of certain of said trunnion hinge sections 27 will engage beneath the faces of certain of said top walls 32 when said cover is pivoted axially of the trunnion hinge sections of one of said lugs 26 to an open position on said body 29 in order to hold said cover pivotally on said body.

In the construction shown the trunnion hinge sections 27 comprise integral portions projecting from the ends of the lugs 26. The container 29 is also provided with end walls 35 and a bottom wall 36. The bottom wall 36 does not extend beneath the lugs 26 so that the lugs 26 are free to pivot downwards in this space when the cover 25 is pivoted open.

The operation and use of this container may be understood from the following:

The cover 25 may be pivoted open from its front or back edge portion. When thus pivoted open the tips of the trunnion hinge sections 27 will ride beneath the top walls 32 and pivotally hold the cover in position while in its open condition. In Fig. 13 the cover 25 is illustrated in a vertically open position, and the dot and dash lines 27' schematically indicate the position taken by the trunnion hinge section 27. Note particularly that the tip of the trunnion hinge section is now located beneath the top wall 32. When the cover is in its closed position, as illustrated in Figs. 7 and 8, it may be removed from the container 29 merely by forcing it upwards so that the trunnion hinge sections 27 are forced out from the socket recesses 34.

It should be particularly noted that the cover may be hinged open on either hinge, while the other hinge acts as a snap latch for holding the cover in its closed position.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. A container, comprising two separate parts, one of said parts being a container body having an open top, the other of said parts being a cover closing said open top, one of said parts having wall portions on opposite sides thereof and said wall portions having open socket hinge sections, the other of said parts having trunnion hinge sections on opposite sides thereof frictionally releasably engaging in said socket hinge sections, 65 said open socket hinge sections being open in a direction towards said part having said trunnion hinge sections in order that said cover may be moved away from said body for moving said trunnion hinge sections out of said open socket hinge sections for separating said parts or said

cover may be pivoted open from one side or its other side by using the trunnion hinge sections which are on the side opposite to the side being pivoted open as hinges for said pivoting operation, said wall portions having top wall sections and end wall sections, said trunnion hinge sections having beveled tips, said open socket hinge sections being extended through said top wall sections and into said end wall sections, those portions of said open socket hinge sections in said top wall sections being congruent with said beveled tipped trunnion hinge sections when said cover closes the open top of said body, and those portions of said open socket hinge sections in said end wall sections forming hinge bearings for said trunnion hinge sections with said trunnion hinge sections lying immediately below said top wall sections in order that when said cover is pivoted open from one side or its other side the trunnion hinge sections which are on the side opposite to the side being pivoted open turn and the beveled tips thereof move out of congruence with said open socket hinge sections for locking said last mentioned trunnion hinge sections beneath the adjacent top wall sections.

2. A container, comprising two separate parts, one of said parts being a container body having an open top, the other of said parts being a cover closing said open top, one of said parts having wall portions on one side thereof and said wall portions having open socket hinge sections, the other of said parts having trunnion hinge sections on one side thereof frictionally releasably engaging in said socket hinge sections, said open socket hinge sections being open in a direction towards said part having said trunnion hinge sections in order that said cover may be moved away from said body for moving said trunnion hinge sections out of said open socket hinge sec-

tions for separating said parts or said cover may be pivoted open by using said trunnion hinge sections as hinges for said pivoting operation, said wall portions having top wall sections and end wall sections, said trunnion hinge sections having beveled tips, said open socket hinge sections being extended through said top wall sections and into said end wall sections, those portions of said open socket hinge sections in said top wall sections being congruent with said beveled tipped trunnion hinge sections when said cover closes the open top of said body, and those portions of said open socket hinge sections in said end wall sections forming hinge bearings for said trunnion hinge sections with said trunnion hinge sections lying immediately below said top wall sections in order that when said cover is pivoted open said trunnion hinge sections turn and the beveled tips thereof move out of congruence with said open socket hinge sections for locking said trunnion hinge sections beneath said top wall sections.
